[57] CLAIM

The ornamental design for a “combined hook and handle for a bag,” as shown and described.

DESCRIPTION

FIG. 1 is an exploded perspective view of a combined hook and handle for a bag showing my new design; FIG. 2 is a front elevational view of a combined hook and handle for a bag shown in the assembled position; FIG. 3 is a rear elevational view of FIG. 2; FIG. 4 is a left side elevational view of FIG. 2; FIG. 5 is a right side elevational view of FIG. 2; FIG. 6 is a top plan view of FIG. 2; FIG. 7 is bottom plan view of FIG. 2; and, FIG. 8 is an enlarged sectional view along line 8—8 of FIG. 2.

The bag is shown in broken lines for illustrative purposes only and forms no part of the claimed design.
